GAS FIRED WATER HEATER

George W. Myler, Columbus, Ohio, assignor to Columbia
Gas System Service Corporation, New York, N.Y.

Filed Feb. 3, 1970, Ser. No. 21,235

Term of patent 14 years

Int. Cl. D23—03

U.S. Cl. D23—86

Fig. 1

Fig. 2

FIG. 1 is a front perspective view of a gas fired water heater embodying my design.

FIG. 2 is a rear perspective view thereof.

The undisclosed side of the gas fired water heater is identical to the side shown in FIGS. 1 and 2.

I claim:

The ornamental design for gas fired water heater, as shown and described.
